STACKABLE MATERIAL HANDLING BOX

William R. Powell, Hubbard, Ohio, assignor to The Powell
Pressed Steel Company, Hubbard, Ohio

Filed Apr. 11, 1972, Ser. No. 243,109

Term of patent 14 years

Int. Cl. D3—99

U.S. Cl. D87—1 R

FIG. 1

FIG. 2

FIG. 4

FIG. 1 is a front perspective view of a stackable material handling box showing my new design;

FIG. 2 is a rear perspective view thereof;

FIG. 3 is a front perspective view showing a modified form of my new design; and

FIG. 4 is a rear perspective view thereof.

The bottom is substantially plain.

I claim:

The ornamental design for a stackable material handling box, as shown and described.
